CLAIM

The ornamental design for the breaching tool, as shown and described.

DESCRIPTION

FIG. 1 is a perspective view of a first embodiment of the breaching tool.

FIG. 2 is a top plan view of the first embodiment of the breaching tool.

FIG. 3 is a first side elevation view of the first embodiment of the breaching tool.

FIG. 4 is a rear elevation view of the first embodiment of the breaching tool.

FIG. 5 is a second side elevation view, on the opposite of the first side, of the first embodiment of the breaching tool.

FIG. 6 is a front elevation view of the first embodiment of the breaching tool.

FIG. 7 is a bottom plan view of the first embodiment of the breaching tool; and,

FIG. 8 is a perspective view of a second embodiment of the breaching tool, like the first embodiment except the dimpling in this embodiment is shown in dashed lines without shading and forms no part of this embodiment of the claimed design.
